UNITED STATES PATENT OFFICE.

WILLIAM C. REDFIELD, OF CINCINNATI, OHIO.

TYPOGRAPHICAL MACHINE.

Application filed April 17, 1924. Serial No. 707,244.

This invention relates to typographical machines, such as linotype machines, wherein the circulating matrices in a composed order for a linotype are transferred from 5 an "assembling elevator" into a receiving channel of a vertically movable "first elevator", which presents it to a mold to enable the type bar or slug to be cast therefrom.

In machines of this class various sets of 10 matrices are employed, as, for instance, matrices bearing a single character; matrices bearing two characters located at different levels thereon, matrices having large face characters, known as "head letters" or "head 15 characters", for casting a slug having an extended width over a single line width. Therefore, different matrix supporting positions are provided, whereby the matrices may be composed and maintained at upper 20 or lower levels as desired, to locate the selected characters in operative position.

In the use of "head letter" matrices as having large face characters, it is a practice 25 to assemble them at the usual or lowest level in the first elevator and provide means for positioning the first elevator to an auxiliary position, or level corresponding to an upper level, with respect to a mold, in order 30 to enable a type metal from the mold to properly reach all portions of such character. The positioning of the first elevator to an auxiliary position being generally accomplished by the use of a socalled filling piece, which when in operative position 35 functions to arrest the movement of the first elevator when it reaches that point in its descent at which the matrix will occupy a proper position with respect to the mold.

The filling piece also functions to control 40 a socalled "vise-automatic" for stopping the machine in the event that the matrices were not properly positioned relatively to the mold, such control being also effective when the first elevator descends to its normal position or point.

After the matrices in the first elevator 45 have been properly positioned with respect to the mold, the mold moves laterally against the matrices, after which the casting is made. 50 As the throwing in of the filling piece is under manual control, it happens that the operator inadvertently fails to make said "throwing in", so that the assembled matrices in the

first elevator are not sustained in their proper mold registering position, resulting in 55 the improper representation of the matrix line to the mold and hence producing a "squirt", or causing damage to the parts or both.

With the present invention, when a line 60 casting is to be made, which requires the first elevator to be sustained in an auxiliary position or level, the first elevator is automatically elevated or adjusted to a position for appropriately bringing the matrix line 65 to registering position with the mold, the mechanism for adjusting the first elevator being actuated by the mold in its movement toward the matrix line.

As a different mold is required for casting 70 "head letters" from that of general characters, the machine is provided with a plurality of molds mounted on a disk, or rotated carrier, whereby the molds are selectively brought to a functioning position. Therefore, the mold carrier is provided with means 75 for cooperating with the mechanism for elevating the first elevator, when the "head letter" mold is moved into its operative position, and adapting first elevator auxiliary 80 positioning mechanism to be out of commission when the various other molds on the carrier are selectively brought to operative position. Therefore, an object of the invention is to provide means for automatically 85 moving the first elevator carrying type matrices in a composed line, to an auxiliary position sustaining the matrices in an appropriate level for mold registry and cooperation therewith.

Another object of my invention is to provide for a machine of the class specified, a lever mechanism actuated by the forward motion of the mold, which will raise the first elevator a sufficient amount to cause it to 95 cooperate with the mold in question.

Other objects and certain advantages will appear in the description of the drawings forming a part of this specification, in which:

Figure 1 is a front elevation of a linotype machine having my invention mounted thereon.

Figure 2 is a section taken approximately 100 on line 2-2, of Fig. 1.

Figure 3 is a section taken on line 3-3,

of Fig. 1, showing the first elevator in raised position and the present invention in operative position during the casting operation.

Figure 4 is a detail view showing means 5 for adjusting the device.

Figure 5 is a sectional view taken on line 5—5, of Fig. 3.

Figure 6 is a detail view of the device unmounted.

10 The present invention is applicable generally to typographical machines, wherein matrices may be assembled at either of two levels, and positioned at either of two levels, in front of a mold adapted to cast slug or 15 type bar therefrom.

In machines of such capacity, the improvement can be easily applied to the commercial machines as an attachment; therefore, the machine organization is not disturbed or its 20 general operation interfered with. The first elevator for casting "head letters" is permitted to descend to its normal position or level for functioning or controlling the so-called "vise automatic", which is in advance 25 of the timed movement of the mold toward the composed line of matrices carried by the first elevator, the first elevator being elevated to its auxiliary position, by lever devices actuated by the mold mechanism in its movement toward the matrices. This, therefore, 30 causes no interference in the general operation of the machine or the safety device employed for its control and avoids any manual control for the auxiliary positioning of the 35 first elevator.

Referring to the drawings 1 indicates the conventional type of mold carrier for supporting a mold 2 or a plurality of molds spaced about the carrier. The carrier is 40 rotatable for bringing the several molds mounted upon the carrier selectively to an operative position. The mold body below the mold cavity or cell 3 is provided with grooves 4 as upper and lower, to respectively 45 receive the lugs 5^a of the matrices 5 assembled in the jaws of the first elevator 6. The elevator is slidingly engaged with the vise cap of the vise frame 7. The mold and its carrier, first elevator and vise frame are 50 of standard commercial structure and their operation well known in the art so that more specific illustration and description thereof need not be made herein for the purposes of the present invention.

55 Lever mechanism for raising the first elevator to its proper level is secured to the block 8 on the vise frame 7. In this position, the levers do not interfere with other parts of the mechanism being mounted upon the block and securely attached to the vise frame.

60 This main lever mechanism comprises a toggle lever, operated by a rod attached at its central pivot. More specifically, I mount upon a plate 10, the surface of which is

parallel to the line of motion of the mold disc, two spaced plates 11, 12, each provided with a semi-cylindrical recess 13. These recesses are opposite to one another, and in them are positioned the two members 14, 15, 70 of my toggle lever. The ends 16, of these members 14, 15, are semi-circular and fit into the recesses 13 cooperating with them to form end pivots for the toggle. The lower one of these plates 11 is secured to the plate 75 10 stationarily and the upper 12 is hinged, thus constituting said upper plate itself a second lever. This form of pivot is found light, staunch and economical, but other forms of pivots are usable and are intended 80 to be included within the scope of this invention.

The rod 17 which actuates the toggle lever is provided with beveled outer edges 18, which cooperate with bearing attachments 19 85 to the plate 10 which form guides for the rod. Any pivotal connection between this rod and the two members of the toggle is sufficient, but I prefer that the rod should be provided at its ends with a semi-cylindrical 90 portion 20 cooperating with two concave surfaces 21, one on each toggle member.

The mold disc is provided with a lug 22 attached to its outer surface and so positioned as to abut the end of the rod. So 95 when the mold disc 1 moves forwardly, the rod 17 is actuated longitudinally, the toggle straightened out and the upper plate 12 or second lever raised. A spring 23 is provided to retract the toggles; one end of said spring 100 being secured to the stationary plate 10 and the other to one toggle member 14.

My toggle mechanism is so positioned on the machine that it is impractical to transmit the upward motion of the plate 12, actuated 105 by the toggle lever, immediately to the first elevator 6, but I accomplish this result by interposing a third lever 25, pivoted to the vise frame 7, above the second lever 12 and adapted to be actuated by it. I find it very 110 practical to screw the pivotal mounting 26 into that opening on the vise frame 7, the upper portion of which is filled by the bolt (not shown) which secures the vise cap 27 to the vise frame. On the other end of 115 this third lever 25 is a lifting rod 28 which extends upwardly through the vise cap 27 and terminates under the head 29 of the first elevator 6, and is thus adapted to raise the same.

A connection between this lifting rod 28 and the third lever 25 is adjustable. Through the end of the lever 25 is screwed a threaded sleeve 30 which is secured by a lock nut 31 on the underside of said lever. The lifting rod 28 is provided with a downwardly extending pin portion 32, adapted to enter this sleeve, but to fit loosely to compensate for the slight difference in the directions in motion of the lever and the lifting rod. 130

When my attachment is used, the mold disc moves forward, engages the rod, which operates the toggle, lifts the second lever, which in turn raises the third lever to which 5 is attached the rod which directly lifts the first elevator, thus, whether the filling piece (not shown) is used or not, my mechanism positions the first elevator at the proper height so that the matrices properly align 10 with the mold slot.

The inherent characteristic of a toggle lever, that the rapidity of motion decreases as the 180° point is reached, causes rapid motion of the first elevator until approximately 15 the correct height is attained, and then relative slow motion as the mold disc comes forward and fits its own groove over the lugs on matrices.

When the mold carrier is rotated to move 20 the mold for the head letters out of commission the stud 22 is moved out of engagement with the rod whereby the lever mechanism is inactive, in any forward movement of the mold carrier.

Having described my invention, I claim: 25
1. In a type casting machine wherein selective molds are carried by a rotatable mold disc and register at different levels with a reciprocating matrix carrying elevator, the registration being completed by a forward motion of the mold disc, the combination of lever mechanism and an abutment, the lever mechanism being operatively attached to the vise frame to engage and raise 30 the elevator above its lowest position and the abutment being provided on the mold disc in association with a mold registering at a higher level and positioned to contact and operate the lever mechanism as the mold 35 disc moves forwardly to raise the first elevator to registering position when the higher level mold is in operative position.

2. In combination with the mold disc, vise 40 frame and first elevator of a type casting machine of the class specified, a plate attached to the vise frame, a toggle lever, one end of which is pivoted to said plate, a rod 45 connected to the center of said toggle lever,

said rod being actuated longitudinally to the mold disc, a second lever pivoted to the 50 upper member of said toggle and said plate, means for transmitting the motion of said second lever to the elevator for the purpose of raising the elevator.

3. In a type casting machine wherein 55 selective molds are carried by a rotatable mold disc and register at different levels with a reciprocating matrix carrying elevator, the registration being completed by a forward motion of the mold disc, the combination of toggle lever mechanism and an 60 abutment, the toggle lever mechanism being operatively attached to the vise frame to raise the elevator above its lowest position and the abutment being provided on the 65 mold disc in association with a mold registering at a higher level and positioned to contact and operate the toggle lever mechanism as the mold disc moves forwardly to raise the first elevator to registering position 70 when the higher level mold is in operative position.

4. In combination with the mold disc, first elevator and mold disc stud lock block of a type casting machine of the class specified, 75 a plate secured to the mold disc stud lock block, a toggle lever with one end pivoted to said plate, a second lever pivoted to said plate and the other end of said toggle lever, a rod pivoted to the middle of said toggle 80 lever, a guide for said rod secured to the plate, a lug on the mold disc adapted to abut the end of said rod and actuate the same, a third lever attached to the vise frame and adapted to be actuated by the second lever, 85 a threaded sleeve on the free end of said third lever, a lifting rod extending through the vise cap, adapted to engage the underside of the head of the first elevator and raise the same, a pin on the lower end of 90 said lifting rod, adapted to fit loosely into the interior of said threaded sleeve.

In witness whereof, I hereunto subscribe my name.

WILLIAM C. REDFIELD.
